(57) **CLAIM**

The ornamental design for a light emitting diode, as shown and described.

DESCRIPTION

FIG. 1 is a front top side perspective view of a light emitting diode in accordance with an embodiment of our new design; FIG. 2 is a top plan view of the light emitting diode in accordance with the embodiment of our new design; FIG. 3 is a vertical cross sectional view of the light emitting diode in accordance with the embodiment of our new design as seen along section line 3-3 of FIG. 2; FIG. 4 is a vertical cross sectional view of the light emitting diode in accordance with the embodiment of our new design as seen along section line 4-4 of FIG. 2; and, FIG. 5 is an enlarged view of an encircled portion 5 of FIG. 3 of the light emitting diode in accordance with the embodiment of our new design.

The broken line showing of environment (the remaining structure of the light emitting diode) in the FIGS. 1-5 is for illustrative purposes only and forms no part of the claimed design. The dash-dot lines connecting the ends of full lines shown in FIGS. 1 and 2 define the bounds of the claimed design, and form no part of the claimed design.

The cross sectional views illustrated in FIGS. 3 and 4 are presented solely for the purpose of clarifying the shape of exterior surface of the claimed design.
